(57) **CLAIM**

The ornamental design for an electric juicer with juice cup, as shown and described.

DESCRIPTION

FIG. 1 is a top, front right-side perspective view of an electric juicer of an electric juicer with juice cup, assembled in accordance with the present design;

FIG. 2 is a rear, bottom left-side perspective view of the electric juicer of FIG. 1;

FIG. 3 is a front view of the electric juicer of FIG. 1;

FIG. 4 is a rear view of the electric juicer of FIG. 1;

FIG. 5 is a right-side view of the electric juicer of FIG. 1;

FIG. 6 is a left-side view of the electric juicer of FIG. 1;

FIG. 7 is a top view of the electric juicer of FIG. 1;

FIG. 8 is a bottom view of the electric juicer of FIG. 1;

FIG. 9 is a top, front right-side perspective view of the electric juicer of FIG. 1 unassembled showing each component of the electric juicer individually;

FIG. 10 is a top, front right-side perspective view of a juice cup from the electric juicer with juice cup, in accordance with the present design;

FIG. 11 is a right-side view of the juice cup of FIG. 10;

FIG. 12 is a left-side view of the juice cup of FIG. 10;

FIG. 13 is a front view of the juice cup of FIG. 10;

FIG. 14 is a rear view of the juice cup of FIG. 10;

FIG. 15 is a top view of the juice cup of FIG. 10; and,

FIG. 16 is a bottom view of the juice cup of FIG. 10.

The claim is directed to the collective appearance of the electric juicer and juice cup. Any broken lines, shown throughout in the drawing figures, are included for the purpose of illustrating environmental structures and form no part of the claimed design.
